US00D819519S

(12) **United States Design Patent** (10) Patent No.: **US D819,519 S**
Whitla et al. (45) Date of Patent: ** Jun. 5, 2018

(54) **VEHICLE REAR CORNER FASCIA**

(71) Applicant: **GM GLOBAL TECHNOLOGY OPERATIONS LLC**, Detroit, MI (US)

(72) Inventors: **Guy W. Whitla**, Rochester Hills, MI (US); **Takahiko Suginoshita**, Rochester Hills, MI (US); **Colin R. Phipps**, Shanghai (CN)

(73) Assignee: **GM Global Technology Operations LLC**, Detroit, MI (US)

(**) Term: **15 Years**

(21) Appl. No.: **29/587,584**

(22) Filed: **Dec. 14, 2016**

(51) LOC (11) Cl. **12-16**

(52) U.S. Cl.

USPC **D12/169**

(58) **Field of Classification Search**

USPC D12/86, 90, 91, 92, 163, 169, 171, 196, D12/216; D3/318

CPC B60R 19/02; B60R 19/04; B62D 25/00; B62D 25/06; B62D 25/08; B62D 35/00;

A45C 13/08; A45F 5/10

Assistant Examiner — Suzanne E Tisdell

(74) Attorney, Agent, or Firm — Reising Ethington P.C.

(57) **CLAIM**

The ornamental design for a vehicle rear corner fascia, as shown and described.

DESCRIPTION

FIG. 1 is a perspective view of the vehicle rear corner fascia; FIG. 2 is a front view thereof;

FIG. 3 is a top view thereof;

FIG. 4 is a bottom view thereof; and,

FIG. 5 is a side view thereof.

The broken lines shown in the drawings depict portions of the vehicle rear corner fascia that form no part of the claimed design.
